UNITED STATES PATENT OFFICE.

JOSEPH HOWARD BUCKLEY, OF WINCHESTER, ILLINOIS.

CAN-OPENER.

1,007,524.

Specification of Letters Patent.

Patented Oct. 31, 1911.

Application filed May 29, 1911. Serial No. 629,990.

To all whom it may concern:

Be it known that I, JOSEPH HOWARD BUCKLEY, a citizen of the United States, residing at Winchester, in the county of Scott 5 and State of Illinois, have invented certain new and useful Improvements in Can-Openers, of which the following is a specification, reference being had to the accompanying drawings.

This invention relates to new and useful improvements in can openers and has for its object to provide a more convenient, inexpensive, and effective can opener, to reduce the cost of construction, to secure a greater 10 scope in operation, and to obtain other advantages and results, some of which may be referred to hereinafter.

Another object of my invention is to provide a can opener that may be used to open 20 cans of various shapes and from the following description taken in connection with the drawing it will be seen that I have provided a can opener especially adapted for square cans and can be easily used on round cans 25 as well.

Another object of my invention is to provide a can opener of this class which will possess advantages in points of efficiency, durability, is inexpensive of manufacture 30 and at the same time being simple in construction and operation.

With the foregoing and other objects in view, the invention consists in the novel features of construction and the combination 35 and arrangement of parts hereinafter described, pointed out in the claim and shown in the accompanying drawings, in which—

Figure 1 is a perspective view of my improved can opener; and Fig. 2 is a longitudinal sectional view showing the opener applied in the position it assumes in the act 40 of cutting the head of the can; and Fig. 3 is a detail view of the cutting knife.

Referring more particularly to the drawings 45 1 indicates a flat bar of any suitable metal, having a handle 2 formed upon one end thereof, and an annular enlargement 3 formed between the bar and the handle 50 which is provided with a circular opening 4. It will be observed that the handle 2 is disposed at an angle with relation to the bar 1 for greater convenience in manipulating the device. The bar 1 is provided with 55 a longitudinal slot 5 adapted to receive the sliding member 6, said member being adapt-

ed to slide within the slot 5 and provided with the flanges 7 adapted to be disposed upon each side of the slot and engage each side of the bar. A piercing point 8 is 60 formed integral with said member and disposed upon one side thereof and adapted to be adjusted to any size can. A disk 9 is rotatably mounted within the opening 4 and having the circular plates 10 and 11 secured thereto and disposed upon each side thereof, which provides the annular flanges 12 65 adapted to be disposed upon each side of the annular enlargement 3 to hold the disk securely within the opening. Secured to the plate 10 is a knife 13 which is provided with a V-shaped cutting edge 14 to prevent the knife from slipping up from the tin which is being cut. Secured to the plate adjacent the knife is the metal guide 15 which serves 70 to engage the edge of the can and guide the knife 13, so that the latter will provide a smooth cut concentric with the edge of the can.

When it is desired to open a can the point 80 8 is pushed through the top of the can at a central point and the bar is then adjusted until the knife 13 is disposed adjacent the inner edge and the guide 15 is disposed on the outer edge of the can, the knife being 85 then pushed through the top to the V-shaped cutting edge 14 and the knife then manipulates by means of the handle 2. It will be readily seen that the disk 9 can be easily rotated so that the knife 13 can be disposed 90 at any desired angle.

While I have shown and described the preferred construction of my invention, it will be obvious that various changes in the details of construction and in the proportions 95 may be resorted to for successfully carrying my invention into practice without sacrificing any of the novel features or departing from the scope thereof.

Having thus described the invention what 100 is claimed is:—

The herein described can opener comprising a body bar having a handle integrally formed on one of its ends and extending 105 at an angle with relation to the longitudinal axis of said bar, said body bar being provided with a longitudinal slot and having a circular opening at the juncture of the handle therewith, a disk arranged in said opening and freely rotatable therein, plates secured to the upper and lower surfaces of 110 said disk and of greater diameter than the

same to provide flanges overlapping upon the edges of the opening in the body bar and on opposite sides thereof to retain said disk in the opening, a cutting knife carried by the lower of said plates and a piercing point adjustably mounted in the slot of said body bar.

In testimony whereof I hereunto affix my signature in the presence of two witnesses.

JOSEPH HOWARD BUCKLEY.
